UNITED STATES PATENT OFFICE.

ROBERT M. KEATING, OF SPRINGFIELD, MASSACHUSETTS.

DESIGN FOR A BICYCLE-FRAME.

SPECIFICATION forming part of Design No. 31,646, dated October 10, 1899.

Application filed September 4, 1897. Serial No. 650,681. Term of patent 14 years.

To all whom it may concern:

Be it known that I, ROBERT M. KEATING, a citizen of the United States of America, residing in Springfield, in the county of Hampden and State of Massachusetts, have invented and produced a new and original Design for a Bicycle-Frame, of which the following is a specification, reference being had to the accompanying drawing, forming a part thereof.

As shown in the drawing, the leading or material feature of my design consists of the upper and lower curved bars diverging or gradually separating from a point adjacent to the crank-hanger upwardly to the head. The top bar is substantially straight from the seat-supporting end downwardly, where it merges in a harmonious curve forwardly and then upwardly, being united to

the head at a point near the top, and the lower curved bar starting from the crank-hanger curves forwardly, upwardly, and then forwardly, and unites to the head near its lower portion, these bars being separated a greater distance at their upper ends than at any other point and gradually approaching each other until they reach a point adjacent to the crank-hanger.

Having therefore described my invention, what I claim is—

The design for a bicycle-frame as herein shown and described.

ROBERT M. KEATING.
